(57) CLAIM

The ornamental design for a seat cover, as shown and described.

DESCRIPTION

FIG. 1 is a perspective view of a seat cover embodying the design of the present invention.

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken line showing of environmental structure is for illustrative purposes only and forms no part of the claimed design.

1 Claim, 3 Drawing Sheets

FIG. 1.

FIG. 6.

FIG. 4.

FIG. 2.

FIG. 7.

FIG. 5.

FIG. 3.

UNITED STATES PATENT AND TRADEMARK OFFICE
CERTIFICATE OF CORRECTION

PATENT NO. : Des. 463,704 S
DATED : October 1, 2002
INVENTOR(S) : Richard J. Hoffmann Jr.

Page 1 of 1

It is certified that error appears in the above-identified patent and that said Letters Patent is hereby corrected as shown below:

Title page.

Item [12], delete "Hoffman, Jr." and replace with -- Hoffmann, Jr. --
Item [76], Inventor, delete "Hoffman" and replace with -- Hoffmann --

Signed and Sealed this

Fourth Day of February, 2003

JAMES E. ROGAN
Director of the United States Patent and Trademark Office
